UNITED STATES PATENT OFFICE.

MARTHA HALOWELL CONNOR, OF BALTIMORE, MARYLAND, ASSIGNOR TO THE TIN DECORATING COMPANY OF BALTIMORE, OF BALTIMORE, MARYLAND, A CORPORATION OF NEW JERSEY.

DESIGN FOR A BOX-COVER.

56,968.

Specification for Design.

Patented Jan. 25, 1921.

Application filed October 27, 1919. Serial No. 333,849. Term of patent 14 years.

To all whom it may concern:

Be it known that I, MARTHA HALOWELL CONNOR, a citizen of the United States, residing in the city of Baltimore, State of Maryland, have invented a new, original, and ornamental Design for a Box-Cover, of which the following is a specification, reference being had to the accompanying drawing, forming a part thereof, wherein—

Fig. 2, is a cross sectional view thereof.

What I claim is:

The ornamental design for a box cover, as shown.

MARTHA HALOWELL CONNOR.
